UNITED STATES PATENT OFFICE.

JACOB E. BLOOM, OF BROOKLYN, NEW YORK.

PROCESS AND APPARATUS FOR THE ELECTRICAL FIXATION OF NITROGEN FROM AIR AND THE PRODUCTS RESULTING THEREFROM.

1,334,590.

Specification of Letters Patent. Patented Mar. 23, 1920.

Application filed August 21, 1918. Serial No. 250,814.

To all whom it may concern:

Be it known that I, JACOB E. BLOOM, major, U. S. Army, retired, a citizen of the United States, residing at Brooklyn, city of New York, in the county of Kings and State of New York, have invented certain new and useful Improvements in Processes and Apparatus for the Electrical Fixation of Nitrogen from Air and the Products Resulting Therefrom, of which the following is a specification.

This invention relates to improvements in present electric processes for fixing nitrogen from air; and has for its object to increase velocity of nitrogen fixation and the amount of fixed nitrogen, without material increase of cost or time; other objects being as described in the specification and claims.

This invention consists in general, in treating the air and gases during, and conducting present nitrogen fixation processes under insulated conditions, by immediately following same with electric adsorption energy, upon and in the air and gases beyond the electric arc, with or without fresh air; or upon adsorption surfaces of sundry coarsely comminuted or granular or crystalline dielectric adsorbents, in an A. C. field, or A. C. fields, under insulated conditions; advantageously of low frequency and of low voltage; and advantageously with low frequency 16 to 25, and low voltage or about 1½ V. or less than the decomposition voltage of nitric acid; and advantageously with the 35 intermittent leading to earth of only uncombined surplus free positive or only uncombined free surplus negative charges ions and electrons, advantageously the former, therefrom while in such field, and in synchronism with the frequency of the A. C. creating said fields.

The fixation of atmospheric nitrogen may be classified into three groups: first group: the combustion of nitrogen and oxygen in the electric arc;—second group: the direct synthesis of nitrogen and hydrogen to ammonia;—third group: the combination of nitrogen with metals or carbids; or the cyanamid process of fixing atmospheric nitrogen. 50 This improvement pertains more especially to or is illustrated by the first group, or the oxidizing the nitrogen of the air in the electric arc, and subsequent thereto.

As additional steps in the present process 55 of nitrogen fixation from air in the electric

arc furnace and thereafter I treat the air, and the nitrogen gases formed at the arc, by conducting same, rapidly and forcibly, advantageously with fresh ionized or ozonized air advantageously from bright sunlight or other ionizing or ozonizing source, advantageously blowing same in the arc furnace near the arc, against an earthing cooling electrode having a ground line with an interrupter hereafter described; and then in a connecting or the same chamber over or near the A. C. arc, blowing same into contact with baffle plates with roughened surfaces, constituting water-cooled electrodes for an A. C. field; and thence into a succession of A. C. fields in vessels connected with each other and the arc furnace, all under insulated conditions, beyond the arc vessel, and holding comminuted adsorption material called adsorbents, advantageously first electro-positive in one of said A. C. fields, and next electro-negative in next A. C. field, or vice versa; and in some cases advantageously with intermittent earth forcing electric connection from an earthing electrode amid the contents in said vessels, for only positive or only negative free surplus uncombined charges, electrons, and ions or the like, in synchronism and automatically with the A. C. current creating said A. C. field, or fields, advantageously of low frequency preferably 16 to 25 cycles with regulable voltage, advantageously less than the decomposition voltage of nitric acid or about 1½ volts.

In some cases and where insulated conditions are difficult of attainment, I use a medium or high frequency A. C. to create said A. C. fields, all under insulated conditions.

Gases in the normal state conduct electricity only to a slight degree. A gas may be put in the conducting state by different means, such as raising its temperature; drawing it from the neighborhood of arcs or glowing metals; or from a space in which an electric discharge is passing; or from ozonizing apparatus; and the like. This conductivity is due to electrons, which form electrified particles or ions, mixed up with the gas. The process by which a gas is made into a conductor is called the ionization of the gas. The movement of free electrons constitutes the current through the gas.

Cold surfaces being the reverse or antithesis of catalytic-like surfaces, I adyan-

- 2
- 5 tageously use hot surfaces with the A. C. field, or hot refractory granules or crystals, as adsorbents, until the oxidation of 2NO etc. into NO_2 is attained.
- 10 5 In general it may be said, the process depends primarily upon adsorption of one or other or possibly both of the reacting gases by the extensive adsorption surfaces acting in the A. C. field and whereby the gases are rendered electrically active and with resulting combination, or increase of velocity of combination.
- 15 10 As a general rule, in the present processes, the reaction velocity falls materially, as the temperature is caused to fall below sundry temperatures, different for different components; with this improvement of conducting the process to attain reactions in the A. C. field, advantageously with adsorption material, the reaction velocity of the higher temperatures is largely or in part maintained, even at the lower temperatures. Again, where in some of present processes, air pressure of several atmospheres is now used, such is dispensed with, and adequate pressure is obtained by my process of using opposing A. C. fields whose opposing alternations act hammer-like on the surfaces of the adsorbents as anvil-like supports.
- 20 15 30 In this process the substances used as adsorbents in the A. C. fields do not constitute components of the products of the process. By the term comminuted adsorbents I include very coarse sizes such as pea-size, so that air and gases can be forced through a mass of such by suction of less than one atmosphere pressure or by force-pump pressure of several atmospheres.
- 25 20 35 As a process, my invention comprises an additional novel step or steps in the present process for the electric fixation of nitrogen from air, in an arc furnace, of treating suitable substances as now used in such nitrogen fixation, such as air, gases and nitrous oxid or peroxid of nitrogen or other nitrogen compounds, by rapidly subjecting the same first in the electric furnace beyond or after the action of the electric arc, and secondly during the passage therefrom in subsequent stages of manufacture, to and through an A. C. electric field or fields or opposing A. C. fields in a suitable conduit into an oxidation chamber or a combination of cooling and oxidizing tube or a series of such tubes or the like advantageously with cooling condensers; and finally likewise in adsorption towers, or the like, with water or alkaline solution, and which I term adsorption towers, all under insulated conditions; thereby subjecting the same to the influence of an alternating electric field or fields or stress, or stresses, or a magnetic or magneto-electric or electro-magnetic or electro-static or oscillating field or silent discharge or a combination of such, or two of the same,
- 30 25 35 from alternating current sources, and which I call or include in the term A. C. field, under control as to voltage, amperage and frequency; and advantageously of low frequency 16 to 25 and of low voltage of about 70 $1\frac{1}{2}$ V. or less than the decomposition voltage of nitric acid; and advantageously of medium voltage where opposing A. C. fields are used, up to about 440 V.; and advantageously with a like field between electrodes beyond 75 the arc, in the arc furnace; and while being rapidly and continuously passed in the above passages beyond the arc vessel through a mass of a suitable coarsely comminuted solid insoluble chemically inert or dielectric adsorbent under insulated conditions; such adsorbents, electro-positive and electro-negative being used in succession, all in suitable insulated or dielectric chambers; the gases, air etc., being passed under pressure or suction continuously and rapidly over and through the interstices of the adsorbents in the successive tubes, and rapidly through the entire apparatus; advantageously with well known cooling means during said passages; 80 and advantageously though not necessarily in all cases, the gases and contents being intermittently automatically connected to ground electrically as regards only the uncombined surplus freed positive or only 85 the uncombined surplus freed negative charges electrons and ions, from the said adsorption vessels or tubes and also from the arc furnace both near the arc electrodes and between A. C. electrodes thereafter. And in 90 some cases I advantageously use the process of opposing A. C. fields as described in my application for U. S. patents applied for December 4th, 1917, Serial Numbers 205,229 (explosives) and 205,228 (dyeing); and I 95 advantageously so do to attain and accelerate the reaction, where there is a material reduction of temperature. And if a much higher voltage than the decomposition voltage of nitric acid be used,—then in addition 100 to the single phase A. C., an additional superimposed direct current is used whose voltage is about $1\frac{1}{2}\%$ of the A. C. voltage. The latter should advantageously not exceed 105 about 440 volts.
- 110 115 All the adsorption tubes in succession need not be provided with A. C. fields; in some cases it suffices with alternate tubes or less; the gases or fluid or liquid passed through the A. C. field in any one tube or chamber 120 carries with it sundry charges into the next adjoining or second tube or chamber, or into a chamber or part of the first tube beyond the electric field; and therefore the latter or second tube can be advantageously used with 125 adsorbent only and without setting up therein another additional A. C. field.
- 130 In the final tower where nitric acid gases are absorbed by water etc., I use advantageously an electro-positive adsorbent as

the adsorptent advantageously with the two opposing A. C. fields; under insulated conditions, without grounding, and where one A. C. field only is used then with the earth-
5 ing of only free positive charges and the like, advantageously to obtain electro-negative groups and state in the resulting compound.

In some cases, I advantageously use a con-
10 tinuous process by reintroducing the waste gases (which otherwise flow into the air from the final adsorption tower), either into the furnace or the electric adsorption tubes together with the fresh air.

15 It is advantageous to avoid introduction of dust. In some cases, the air is first purified and ionized or ozonized and then treated similarly in like electric adsorption tubes before being mixed with the gases in said 20 tubes beyond the furnace. Similarly NO can also be made and advantageously similarly treated by the silent discharge with very little elevation of temperature.

It is advantageous to conduct the whole 25 process continuously and simultaneously and as expeditiously as practicable and under insulated conditions so as to complete same while all the air and gases are in a state of ionization.

30 As an apparatus, my invention comprises an electric arc nitrogen furnace in combination advantageously near the arc, with an earth electrode water cooled and electrically connected through an interrupter passing to earth only one kind of current charge electron or ion, advantageously positive; and in the arc chamber with an A. C. field advantageously between plate cooling electrode terminals; and connected with and leading 35 from the arc chamber, a tube conduit or chamber or chambers advantageously of or lined with refractory material, leading from the furnace to a tube or succession of several tubes of cooling and oxidation acid proof refractory lined chambers; and advantageously in the final liquid adsorption, i. e., adsorption towers; each with and having a mass of a suitable coarsely comminuted solid insoluble adsorptent, first of one sign in one 40 tube and then of opposite sign in the ensuing tube; with means for forcing, blowing and sucking air and gases therethrough and through the whole system continuously; means for producing and maintaining, in 45 and around said mass and contents, in each or part of said tubes and chambers, a suitable alternating current field or fields under insulated conditions, such as between terminal electrodes, or an induced magneto electric or electro-magnetic or electro-static or oscillating field or other fields or silent discharge, from A. C. source and which I generally term an A. C. field; and with means of control thereof, especially as regards voltage, 50 amperage and frequency; the said A. C.

source being in some cases advantageously a single or two-phase A. C. of low frequency, and low voltage; and in some cases by opposing A. C. fields of medium to high frequency; and with means of supplying to and withdrawing from said furnace and ensuing tubes and chambers, under pressure or suction, either intermittently or continuously, the said gases and advantageously ionized air etc., to be treated; and with means of 55 cooling the said gases and chamber and adsorption material; all with or under insulated conditions; and with means for electrically connecting the moving gases and contents in said furnace or chamber or conduit tubes, to earth, to automatically ground only either positive or only negative free uncombined charges, electrons, and ions, through an earthing electrode in the tube or chamber, and an insulated ground wire, having in series an exterior insulated electric step up transformer, with condenser; or what I call a grounding coil, to wit: a magnetic core with a coil of insulated wire or the like following;—or a static machine or 60 the equivalent in connection with an insulated automatic adjustable synchronous interrupter called a selector or the like, passing through such forcibly with increased voltage to earth only positive or only negative electrons, ions and charges, in synchronism with the frequency and one kind of the alternations of each cycle of one of the said A. C. creating said A. C. fields, and holding 65 back or insulating the complementary or other alternation or charge of the A. C. on the contents in the A. C. field; and in some cases, with means of removing and replacing all or part of said adsorptent; with means of withdrawing from said tubes and 70 chambers the liquid condensations of said gases; the said interrupter is advantageously a rotary interrupter or a pendulum interrupter as hereinafter described though I do not restrict myself thereto; such selector is electrically connected with and in combination with (1) one terminal of the static machine or grounding coil or secondary coil of a step-up transformer and the like; and (2) the other terminal thereof being connected with the earthing electrode or the like in the A. C. fields; and (3) the ground or its equivalent; constituting together what I term electric ground forcer. In present arc furnace in some cases, I advantageously use such grounding, through an added earthing electrode, water-cooled, placed near the arc, in the path of the air at a distance from the arc electrodes greater than between the electrodes forming the arc; and advantageously a selector to pass only positive to ground; thereby holding back and allowing accumulation of negative charges on the NO and 2NO and thereby prevent or largely diminish the return to at- 75 80 85 90 95 100 105 110 115 120 125 130

mosphere N of the fixed N compounds; and to attain electro-negative groups; and the present tendency of the N and O to reassemble as air at the lower temperatures incidental to removal, both during and after the removal, is largely diminished.

I use the term "selector" to describe the synchronous rotary interrupter, or the synchronous magnetic pendulum interrupter adaptable to performing similar functions; that is to say, to have the function of selecting and passing therethrough to earth only one kind of alternation charge electron and ion; that is to say either only positive or only negative.

I use the term "earth electrode" to include a plate or wire, or gauze or the like, to concentrate and gather thereon in the A. C. fields, the freed unbalanced uncombined surplus electric charges, electrons, and ions, intended to be duly grounded, through the selector above described, which electrically selects and permits to pass therethrough only the positive or only the negative, to the ground line therefrom leading to earth, advantageously through a booster, or the like, to increase the voltage to earth.

When combinations are to be effected between freed positive elements such as O and negative constituents such as NO,—advantageously all grounding should be avoided; or even with this intermittent grounding system, there may be no grounding effect attained, because there may be no free surplus uncombined charges, electrons or ions. Hence the importance of empirical tests.

In gases especially, the negative ions have a velocity materially greater than positive; therefore it is most important to insulate the negative; or advantageously adjust the earth ground forcer to pass only the positive and thus to prevent the passage of, and insulate only the negative, permitting the passage to earth of free uncombined surplus positive, if there be any such.

The earth electrode is advantageously made of material which is acid-proof and refractory and not affected by the high temperatures or the acid; and advantageously a good electrical conductor, and advantageously non-magnetic, such as carbon (porous) or graphite.

When the negative is to be earthed, then where the earth electrode is made of metal, I advantageously use electro-positive metals which most readily discharge or lose negative charges,—such choice being largely governed by the order of metals, the same as Volta's series for contact electricity, to wit: rubidium, potassium, alloy of potassium and sodium, lithium, magnesium, thallium, zinc, lead, tin, iron, copper, graphite, etc.

Or in the order according to Pfaff, of zinc, cadmium, tin, lead, tungsten, iron, bis-

muth, antimony, copper, silver, uranium, tellurium.

And conversely in the reverse order where the positive is to be earthed. Or for economy, I use a combination of such metals as for instance, iron coated or glazed with potassium or zinc, etc., bearing in mind also temperature and inertness as regards chemical combination with the gases, acids, etc.

As a product, my invention comprises an electrically adsorbed or fixed nitrogen compound homogeneous and of increased stability and density over the density as obtained by present methods of nitrogen fixation. Moreover, in many such products, I attain the nitrogen and nitrous or nitric acid in the form of electro-negative groups which are peculiarly advantageous in or for the functions desired therefrom.

I attain my improvements by the mechanism or apparatus illustrated in the accompanying drawings, in which similar letters and numbers refer to similar parts throughout the several views; and the arrows point the direction of the flow of gases.

Figure 1 is a diagram of vertical section of an electric arc furnace; supported on insulators, I, with an earthing electrode H near the arc, with a ground line having an interrupter or selector X; and with an A. C. field A. C. between electrodes advantageously water cooled above the arc, and with intermittent electric ground forcer X from chamber walls H' as an earth electrode; with air pump Z; all on insulator supports I.

Fig. 2 is a diagram of a vertical longitudinal section of one of several electric adsorption tubes or conduits or vessels, U-shaped; with door D for inserting adsorbs, etc.; with an electro-positive adsorbent Ad, with an A. C. field between electrode plates, advantageously interiorly water cooled; with faucet F for withdrawing liquid condensations; supported on insulators I, and with high pressure air and gas pump Z with sundry tubes from several arc furnaces, for forcing through the adsorbent Ad.

Fig. 3 is a diagram of a vertical longitudinal section of an electric adsorption tube, U-shaped, of non-magnetic metal which serves as H, with an electro-negative adsorbent—Ad, to follow the preceding tube or vice versa; and with an induced A. C. field therein created by an open core transformer core C; with grounding from H through interrupter X.

Fig. 4 is a diagram of an electric adsorption tube in perspective having one complete turn around one arm of and insulated from a closed core C transformer T; the tube at H where it incloses the adsorbent Ad, being advantageously connected to earth through interrupter X and static machine A A'.

showing adjustment to force negative to earth 77.

Fig. 5 is a diagram of an electric adsorption tube in perspective, having a half turn, 5 U-shaped, around one arm of and insulated from a closed core C of transformer T; and having a refrigerating tube W of brine or the like passing therethrough and surrounded therein by the adsorptent—Ad, 10 through which the gases and air are forced and simultaneously cooled; with earthing from H, which may be the metal tube, through interrupter X and static machine to force to earth the positive.

Fig. 6 is a diagram of a form of one of several final adsorption towers or advantageously like the plate tower, wherein the gases enter at the bottom, with a water spray entering at the top,—such tower being filled 20 with the adsorptent; and in which tower an A. C. field is created between electrodes taking the place of the plates as ordinarily used in plate absorption towers and with electric earth forcer X.

Fig. 7 is a diagram of an electric ground forcer, to wit: an automatic electrical pendulum interrupter or selector 91—91''' pivoted at about center, with polarized relay 90, like Fig. 9 in my application for 30 patent Serial No. 205,229 filed December 4th, 1917, operated in synchronism with main A. C. creating the A. C. field in adsorption tube by a shunt 50 therefrom; and automatic electric connection with static machine A A' and with earth electrode H, of adsorption vessel, and ground 87.

Fig. 8 is a diagram of an electric rotary interrupter or selector 103—104 operated by a shunt 50 from main A. C. and electrically connected with static machine A A', earth electrode H, of adsorption vessel and ground.

Fig. 9 is a diagram of another type of electric ground forcer showing ground wire 45 from earth electrode H to selector or interrupter X with 2 point switch S adjustable for passing only positive or only negative to an electric condenser and thence to ground with greatly increased voltage through step-up transformer which has a primary coil, a shunt 50 from main current A. C. creating the field in the adsorption tube; this type being for use in lieu of above static machine.

Fig. 10 is a diagram of a grounding coil of very many turns around a magnetic open core, for use in lieu of condenser and transformer of Fig. 9, with similar connections through switch S, to increase the voltage to 55 earth of only the positive or only the negative, for use in lieu of above static machine. I. advantageously insulate the entire apparatus by supporting same on insulated material porcelain, glass, ebonite, etc.

Fig. 11 is a diagram of longitudinal sec-

tion of twin adsorptent tubes with or without an A. C. field, the one PAT holding a mass of positive adsorptent, and the other NAT holding a mass of negative adsorptent and through which there is advantageously 70 first forced from the arc furnace Fig. 1, the air and gases, divided from the one furnace, or from two separate furnaces; the gas from PAT, largely thereby charged negatively, meets at N, the gas from NAT, largely thereby charged positively; and thereupon combination of the + and — gases results in tube or chamber N; and whence the gases are forced anew and continuously into another tube or chamber advantageously an 80 electric adsorption tube with an A. C. field.

When the electric arc furnace is of the Birkeland-Eyde furnace type, where the arc is now deviated magnetically by means of a single phase magnetic field,—to spread 85 the arc flame over a large area, my improvements advantageously include the placing of an earthing electrode or plate H, water cooled, along or parallel to the arc flame, and at a distance therefrom greater than the 90 distance between the electrodes creating the arc; or otherwise, so as to prevent short circuiting; and I connect said earth electrode to ground through an exterior insulated interrupter or selector as hereafter described 95 and advantageously adjusted to pass only free uncombined positive alternation of the A. C. charges, electrons and ions to earth, the other complementary alternation and charge being prevented from passing therethrough and thereby insulated.

I improve said arc furnace type further, as illustrated by diagram in Fig. 1 by providing an A. C. field of low voltage and frequency between water-cooled electrodes of 105 extensive roughened surfaces placed close together, acting as baffle plates in the furnace chamber, and above or distant from the arc, the air and gases from the arc being blown between and around the baffle electrodes into the connecting adjoining electric adsorption tube.

The electrical adsorption tube or chamber is advantageously constructed in the shape of the letter U as illustrated in diagram in 115 Fig. 2, or 3, or 4, or 8 and so that the adsorptent can be conveniently packed and held in position in the bend or bottom of the U, advantageously through a door-way conveniently placed toward the top or upper 120 part of the U; and through which the electrodes for creating an A. C. field can be conveniently placed and repaired. At the entrance for air and gases, a powerful air force pump Z is placed for the due receipt or suction of the air and gases from the furnace, advantageously with a different supply pipe from each of several furnaces, Fig. 2, and to be jointly forced by Z through the first electric adsorption tube and field.

These tubes are advantageously made either of porcelain or stoneware or earthenware or glass or other insulating refractory material; or they may be made of non-magnetic metal, lined with acid-proof refractory insulating material; or they may be made advantageously of a non-magnetic metal lined with acid-proof coating and refractory supported on insulator or petticoat supports 1; advantageously where the A. C. field is created between electrodes; and in order to handle the large volumes of air and gases for nitrogen fixation and the like, these tubes are advantageously made of such metal, the joints being sealed; these tubes having insulating connections with ensuing tubes; such construction lends itself advantageously for manufacturing any parts and the due belting together, and for due repair thereof. Again such construction is advantageous for adapting the return bends system and cooling methods used in refrigerating apparatus; illustration as where an interior tube, such as W in Fig. 5 is inserted 25 in the U-shaped adsorption tubes, advantageously of pottery, for the passage of cold refrigerating liquid brine or ammonia or the like to chill the surrounding gases as they are forced through the adsorption material 30 which surrounds the refrigerating tube.

Again where the adsorption tube is of a non-magnetic metal, it takes the place of, and acts as the earth electrode H, heretofore described, and which is electrically connected to earth through the electric earth 35 force herein described for forcing to earth with increased voltage only the positive or only the negative surplus uncombined free charges, electrons and ions.

Again, at the lowest part of the bend of such U-shaped tube as in Fig. 2, there is conveniently placed a vessel F for receiving the condensed gases in liquid form, and with a faucet for the periodical withdrawal therefrom.

In lieu of the ordinary air blower system as now used to force air into the electric arc furnace, I advantageously use a most powerful air force pump system with sufficient power to force the air and ensuing gases continuously through and from the arc furnace and then through a succession of several sets or pairs of electric adsorption tubes, one of each set being filled with 50 coarsely comminuted positive adsorbents, and the other following with negative adsorbents and thence into the liquid adsorption towers.

The said adsorbent tubes are also advantageously cooling tubes and simultaneously function as oxidation chambers, and in which the hot gases are gradually cooled from about or over 1000° C at the entrance to the first tube, to about 50° C in the final

tubes whence the gases enter the adsorption 65 towers.

It will be understood that as the hot gases are led from one adsorption tube to the next tube, the gas piping can be led through steam boilers, as at present, for the due 70 heating thereof.

It will be understood that the number and characteristics of the final adsorption towers will be the same as are now used; such now generally consist of 3 series of stone towers 75 about 20 meters high and about 6 meters internal diameter and each series comprises five towers, namely 3 acid and 2 alkali towers. With my improved system, I use in the 3 acid towers an electro-negative adsorption material; and with the two alkali towers I use electro-positive adsorption material; all under insulated conditions; and with an A. C. field therein advantageously between electrodes, and having the electrodes 80 support the adsorption material.

The passage of the gases from tower to tower is forced with air compressors or force pumps, advantageously of aluminum fans or pistons respectively, or substances 90 not affected by the acid.

As a general statement, at the electric arc, the nitrogen and oxygen of the air directly unite to form nitrous oxid; thereafter in the subsequent A. C. field between electrodes in 95 the furnace or the like, and again thereafter in the adsorbent tubes, the NO or nitrous oxid takes up oxygen from the air to form nitrogen peroxid; and subsequently in the towers the nitrogen peroxid is absorbed by 100 the water with the production of nitric and nitrous acid; or is absorbed by a basic solution to form nitro-lime, etc., or other basic compound.

As a general rule waste gases flowing 105 from the final tower comprise very little nitric gas and are generally allowed to go to waste, but if it be found advantageous to save the same, then the air and waste gases are led by suitable piping to the air force 110 pump at the furnace advantageously heated in coils encircling the furnace or cooling adsorption tubes, so that thereby there is introduced into the furnace and ensuing adsorption tubes, not only the waste gases 115 heated but also ionized.

All of the apparatus, furnace, towers, tubes, and the like are supported on insulators so that the entire operation may be conducted under insulated conditions, continuously and rapidly.

In some cases wherever the A. C. field (in insulated vessels, chambers, tubes, etc., to which the materials are subjected) is created between electrodes, the casing or framework or an exposed portion thereof as H' Fig. 1 of such container or vessel, supported on insulators, may be advantageously uti-

lized in lieu of or as the earth electrode H, intermittently connected to earth through an interrupter or electric ground forcer as described. Care must be exercised to keep the 5 distance of the electrodes from the casing, greater than between the electrodes.

I advantageously use a compressor blower or high pressure air pump to blow and force the air and gases under pressure of many 10 atmospheres, so as to rub the air rapidly and forcibly through the tubes filled with coarse comminuted angular adsorbents or through narrow tubes having roughened surfaces—in some cases, roughened by numerous punctures; and more especially so doing prior 15 to injecting the air, preferably hot, into the electric furnace, and preferably cooled into electric adsorption tubes; and quickly chill the gases NO and air, upon leaving the arc; 20 and also in injecting the gases with or without fresh air, into or through the electric adsorption tubes as described and with A. C. fields to accelerate reaction during the cooling; and advantageously with electric 25 ground forcer as described.

In the carrying to ground of the free uncombined surplus only positive or only negative charges, electrons and ions, which may be set free when the chemical combinations,—in this case, the oxidation of the N,—take place in the A. C. field, inasmuch as the same are very faint, I increase the forcing to ground thereof by increasing the voltage through a step-up transformer Fig. 9, 30 or static machine Fig. 4, or grounding induction boosting coil Fig. 10, following an interrupter in the ground line which allows only the positive or only the negative to pass therethrough.

40 Thus, in some cases, I advantageously drain to earth negative electrons or free uncombined surplus negative ions or charges, by connecting the ground wire from the earth electrode H surrounded by the material, or the metal casing H of the tube or chamber holding the mass of adsorbent and material being electrically treated, with the positive terminal A of a static machine or the like, shown in diagram Fig. 4, advantageously adjusted to avoid sparks, but with silent discharge between terminals. And conversely I drain positive electrons or free uncombined surplus positive charges or ions by connecting the ground wire from 45 earth electrode H with the negative terminal A', Fig. 5, of static machine or the like: the other terminal in each case being advantageously grounded, as at 77 and 87 respectively.

50 Again, in some cases, I use in the ground wire a magnetic mechanical pendulum interrupter Fig. 7, as a part of the electric earth forcer, adjusted so that in one swing, it makes electric contact with the positive terminal of the said static machine, to discharge

to earth free surplus uncombined negative electrons or ions; and in the opposite swing of the pendulum, it makes electrical connection with the negative terminal to discharge free surplus uncombined positive electrons 70 or ions,—unless the same is previously switched out of the circuit as by switch S. And likewise opening switch S' and closing switch S when the negative is to be grounded; and so that when surplus negative electrons are to be earthed, then the negative terminal of the static machine is connected to earth; and vice versa, when positive charges are to be earthed, the positive terminal is earthed. This is illustrated by diagram Fig. 7, by extending the length of the ordinary pendulum 91 beyond or above its pivot 91''; so that when one end of the pendulum 91'' makes contact with the positive terminal A of the static machine through 80 cone-contact 95 of the pendulum of the interrupter, to discharge negative electrons or ions, then simultaneously the opposite end 91 makes contact 99 with the negative ground wire, from the negative terminal A'; 90 and conversely when the one end of the pendulum 91''' in its ensuing swing makes contact with the negative terminal A' through 94—94'—94'' to discharge positive electrons or ions from H, then simultaneously the 95 opposite end of pendulum 91 automatically makes contact 98 with the positive ground wire,—the negative ground wire 77 at contact 99' being then automatically severed. The pendulum interrupter is operated by 100 electro-magnets 90 by a shunt 50 from the main A. C. circuit in synchronism with the frequency of the A. C. field surrounding the earth electrode plate H in the chamber or vessel through which the gases or substances 105 are passed or treated.

Again, in lieu of a pendulum interrupter as above described, I advantageously use a synchronous rotary interrupter, which I also call a selector, such as shown in diagram 110 Fig. 8, driven by an A. C. motor 101, driven by the A. C. shunt 50 from the main circuit creating the A. C. field, on an insulated shaft 102, with metal cylindrical collector rings 103 and 104, with projecting teeth or contacts 94 and 95 respectively, mounted on insulated cylinder 105, as of ebonite. In the diagram Fig. 8, A and A'—represent the terminals of static machine, driven by any suitable motor or preferably by a motor in synchronism with the A. C. motor 101 driving the rotary interrupter shaft 102, revolved by an A. C. motor having the same frequency as the A. C. field or the A. C. current creating such field. Or A A' represent 120 the terminals of an ignition induction coil, or the like; H is the ground electrode or the like in the vessel or tube inclosing said A. C. field and adsorbents and materials being treated therein; 94'' and 95'' are conducting 130

brushes electrically connected with the terminals A'— and A and bearing continuously on the insulated collector rings 103 and 104 respectively, which are insulated from each other by and supported by the insulator cylinder 105, fixed upon and revolving with shaft 102; 94 and 95 are metal contact points or lugs or teeth projecting from the metal collector rings 103 and 104 respectively—and 10 whose surfaces are continuous therewith; 94' and 95' are metallic brushes connected by wire with the grounding electrode H (H—H+) in the vessel; the contact point being arranged to contact throughout the semi-circle or in some cases advantageously at the peak of the cycle of the A. C. or its maximum amplitude; 94''' and 95''' are brushes to ground 98 and 99 plus and minus respectively.

20 The operation of this A. C. selector is as follows: When the A. C. motor is duly driven by a shunt 50 from the main A. C. circuit, the interrupter selector revolves; and each successive half revolution carries to 25 ground in due succession, first if there be any such, the surplus free positive uncombined electrons or ions or charges through or from ground plate H to ground 98; and to effect such only, the uncombined free 30 negative electrons or charges to 99—, either 94''' or 95''' must be permanently cut out by a switch S or S' in the ground line; as for instance when it is desired to hold back and prevent the discharge of all negative 35 charges, switch S would be cut out; or 95' brush withdrawn from possible contact with 95.

In the operation of the selector if it be desired to ground only the positive, then 40 switch S' is closed and switch S is opened; a double switch may do both with one motion.

When the rotation of shaft 102 starts clockwise, contact point 94 contacts with 45 brush 94' from H; and electrically connects with A—the negative terminal of static machine, through 103; and simultaneously contact 95 meets with brush 94''' thus making electrical connection to ground 98 from positive terminal A through 104 and 95''. There is then, no ground connection with 99 or for negative charges; the circuit being H to 94' to 103 to 94''' to A' through static machine to A to 95'' to 104 to 94''' to earth 98. 50 But if it be desired to ground the negative only, then switch S is closed and switch S' is opened; and thereupon, in ensuing half revolution 180°, contact 94 is in touch with 95''' to ground 99— connection A'— to ground; and contact 95 contacts with 95'' to H— and through 104 and 95'' electrically connects with A; and the circuit being H— 55 to 95'' to 104 to 95''' to A through static machine to A'— to 94''' to 94 to 95''' to earth 99—; and there is then no ground connec-

tion with 98 or for positive charges. And so on, for each half cycle of the rotation. In some cases where chemical compounds are formed in the A. C. field, there may be set free either only (1) free surplus uncombined negative charges or electrons or ions, or (2) only free positive charges or electrons or ions, or (3) both in due succession; such can best be determined empirically by an actual test upon the results; in which tests: 70 With apparatus Figs. 7 and 8, for (1) the switch S is opened to cut out entirely the positive from plate H to ground and switch S is closed; or for (2) the switch S is opened to cut out entirely the negative from plate H 75 to ground and switch S' is closed; or for (3) where both switches are closed.

I do not restrict myself to the apparatus as described such as the particular interrupter and static machine and the like, but 80 may use other analogous apparatus to attain the same end.

As an adsorbsent or comminuted adsorption material in my A. C. fields, I have described sundry such in my above U. S. 90 patents and patents applied for; and which are generally suitable in this improvement. Most of such are not electrical or magnetic substances being mostly non-conductors; but I do not restrict myself to such only.

Two or more such adsorbsents may be simultaneously used; advantageously by uniform mixing when comminuted; but all such should be electro-positive or all electro-negative.

100 It is advantageous to use such adsorbsents in crystalline or angular form, about pin-head or quarter-inch or pea size, where obtainable without excessive cost; or in crushed comminuted grains. The adsorbsent for air 105 and gases will not be comminuted as finely as for liquids but will be coarse, advantageously pea-size or 10 to 20 mesh, so as to permit of ready passage of the gases which will be blown through the chambers by 110 means like forcing air through twyers in blast furnaces, or by air force pump or the like whereof the blades of rotary air compressors are advantageously made of hard wood or acid proof material.

115 I advantageously operate my process and attain my improvement by passing the air and gas mixtures from the arc, Fig. 1 and the like, rapidly through the above successive A. C. fields under insulated conditions 120 and under adequate force into and through said electric adsorption tubes or chambers Figs. 11 and 2 and 3 and 4 and 5, or more of such, each advantageously holding masses of comminuted solid adsorption material, 125 either electro-positive such as corundum (Al_2O_3), or electro-negative such as silica, or advantageously each in succession and advantageously at gradually reduced temperatures down to 50° C., simultaneously 130

having or creating in the said tubes or chambers an alternating field, preferably of sixteen or twenty cycles, or less than 100 cycles, low frequency, and with low voltage and 5 advantageously with intermittent earthing as described; and the same being advantageously cooled by well-known methods.

I advantageously conduct the process which results in ionization of the air and 10 gases in the furnace, rapidly and under insulated conditions so as to retain the ionization of the air as long as practicable; I advantageously subject such air preceding its introduction, to a process akin to ozonization 15 of air. Again, when fresh air is introduced anywhere into the furnace or into any of the tubes, it is advantageous to do so in the form of pure ionized air or of electrically charged air as by friction or static or magnetic 20 neto-electric forces in such similar adsorption tubes; and I advantageously use air from a bright clear sunlight, which results in an increase in its permeability as regards ionization.

25 And I pass the gases finally through present absorption towers, or plate towers, Fig. 6 or the like, substituting for present plates, electrodes with A. C. field or fields in the tower, and with adsorbents preferably 30 finally positive between the electrodes, and with counter-injections of water sprays and the like, or lime water, or basic solutions thereby constituting or changing absorption towers into what I call adsorption towers, or chambers, duly attempered, and under insulated conditions, and advantageously using the electric ground forcer from the tower contents to earth, to pass thereto only the one kind of freed or unbalanced charges, 35 electrons and ions, preferably finally the positive, in synchronism as regards frequency with an A. C. creating one of said A. C. fields in the tower or the like. Or in the present absorption towers with the broken stones or solids as now used, I advantageously use the same A. C. fields therein as with my comminuted adsorbents. The electrodes are advantageously of the type of hollow water-attempered electrodes. And 40 likewise as regards NO gases from any source, to convert same previously to NO₂, and then to H₂NO₃ in the adsorption tower with water and the like. This electrode A. C. adsorption system is adaptable also in 45 other forms of absorption towers.

In the final adsorption tower nearly all the nitrous fumes escaping prior condensation, are absorbed by the down-streaming water spray facilitated by adsorption on the 50 adsorbent surfaces in the A. C. field so as to form a dilute nitric acid; and in some cases a lime water is used to form a calcium nitrate suitable as fertilizer; and similarly with other absorbents.

55 When the said comminuted adsorption

materials are electro-positive, then the interrupter is adjusted to pass only the surplus free positive charges, electrons or ions to earth; and vice versa. It is advantageous to make an empirical practical test to determine whether it is most advantageous as regards percentage of the desired product obtained, to pass only the positive or only the free negative charges electrons and ions to earth through the interrupter, and whether 70 to use first electro-negative or positive adsorption material, or vice versa, or both in succession.

I do not restrict the process as described to the particular gases above named; but 80 also apply the same to obtain combinations of other gases, or condensations thereof, or combinations of the gases with absorption liquids or solids and the like.

Substantially the same process and electric adsorption tubes and accompanying apparatus as described are applicable in the manufacture of the compound gas, to wit: Ammonia, NH₃, by duly mixing three volumes of hydrogen with one of nitrogen from 90 air, while forcing same with adequate pressure through the comminuted adsorbents, as above described, advantageously in an A. C. field under insulated conditions, at high temperature advantageously about 500° C.; and 95 even with lower temperatures the above process is applicable with about the same reaction velocity as with the much higher temperature. In general H is positive; and N is negative; and when such are duly charged 100 accordingly as above described, when they meet on the surfaces of the adsorbents, advantageously activated in the A. C. field, then chemical combinations thereof are activated and quickly attained.

105 I claim:

1. In the electrical fixation of nitrogen from air, in the arc furnace processes, the additional step of conducting present processes therefor under insulated conditions, 110 and likewise in A. C. fields beyond the arc furnace.

2. In the electrical fixation of nitrogen from air, in the arc furnace processes, the additional step of conducting present processes therefor under insulated conditions, and in A. C. fields beyond the arc furnace, with the leading to earth from the gases and air in the furnace, and beyond, of only the 115 one kind of electrical charge, electron and ion in synchronism with the frequency of the A. C. current creating the said field.

3. In the electrical fixation of nitrogen from air in the arc furnace process, the additional steps of conducting present processes therefor under insulated conditions and of first ozonizing and ionizing most of 120 the air used therefor.

4. In the electrical fixation of nitrogen from air, in the arc furnace process, the ad- 125

ditional step of conducting the present processes for treating the air and gases beyond the electric arc, which consists in subjecting the air and gases to A. C. fields, under insulated conditions, while being forcibly and rapidly conducted through successive masses of comminuted suitable dielectric adsorption material.

5. In the electrical fixation of nitrogen from air, in the arc furnace process, the additional steps of conducting the present processes under insulated conditions and subjecting the air and gases beyond the electric arc to A. C. fields under insulated conditions while being forcibly and rapidly conducted through masses of comminuted suitable dielectric adsorption material; and with the leading to earth therefrom of only the one kind of free surplus uncombined electrical charges, electrons and ions in synchronism with the frequency of the A. C. creating the said fields.

6. In the electrical fixation of nitrogen from air in the arc furnace process, the additional steps of conducting the present processes and in subjecting the air and gases beyond the electric arc, under insulated conditions, to opposing A. C. fields under insulated conditions while being forcibly and rapidly conducted through a mass of comminuted suitable dielectric adsorption material of the one sign; followed by like treatment while the gases and air are being forced rapidly through a comminuted suitable dielectric adsorption material of opposite sign to that of the previous adsorption material.

7. In the electrical fixation of nitrogen from air in the arc furnace process, the additional steps of conducting the present processes under insulated conditions, and also subjecting the air and gases beyond the arc furnace, to A. C. fields under insulated conditions while being forcibly and rapidly conducted through masses of comminuted suitable dielectric adsorption material, and finally forcing the air and gases similarly into and through comminuted suitable dielectric adsorption material as the adsorbent, in absorption towers with a liquid absorber.

8. In the electrical fixation of nitrogen from air, the additional steps of treating the air and gases beyond the arc furnace which consists in subjecting the air and gases to an A. C. field and then forcing same through a mass of comminuted suitable dielectric adsorbents under insulated conditions.

60 9. In the process for the electrical fixation of nitrogen from air in an arc furnace, the additional step of conducting the process under insulated conditions and with the leading to earth from the gases, as and when formed at the arc, only the one kind

of free uncombined charge, electron, ion and the like, and so doing in synchronism with the frequency of the A. C. which creates the arc.

10. In the process of oxidizing nitrous 70 oxid and peroxid of nitrogen gases and the like, the additional step of conducting the present process in an A. C. field under insulated conditions.

11. In the process of oxidizing nitrous 75 oxid and peroxid of nitrogen gases and the like, the additional step of conducting the present process in an A. C. field under insulated conditions; and with the leading to earth from the gases and air of only the 80 one kind of electrical charge, electron and ion with increased voltage and in synchronism with the frequency of the A. C. creating such field.

12. In the process of oxidizing nitrous 85 oxid and peroxid of nitrogen gases and the like, the additional step of conducting the present processes in A. C. fields under insulated conditions; and while the gases and air are being forcibly and rapidly conducted 90 through a mass of comminuted dielectric adsorption material.

13. In the processes of oxidizing nitrous 95 oxid and peroxid of nitrogen gases and the like, the additional step of conducting the present processes in A. C. fields under insulated conditions; and while the gases and air are being forcibly and rapidly conducted through a mass of comminuted dielectric adsorption material, together with ozon- 100 ized air.

14. In the process of oxidizing nitrous 105 oxid and peroxid of nitrogen gases and the like, the additional step of conducting the present process in an A. C. field under insulated conditions; and while the gases and air are being forcibly and rapidly conducted through a mass of comminuted suitable dielectric adsorption material; and with the leading to earth therefrom of only the one 110 kind of free surplus uncombined electric charges, electrons and ions with increased voltage and in synchronism with the frequency of the A. C. creating the said A. C. field.

15. In the present process of absorbing and combining nitrous oxid and nitric oxid and the like, with water and alkali solution and the like, the additional step of conducting the same in A. C. fields under in- 120 sulated conditions.

16. In the present processes of absorbing and combining nitrous oxid and nitric oxid and the like with water and alkali solution and the like, the additional step of conducting the same in an A. C. field under insulated conditions, and with the leading to earth therefrom with increased voltage, of only the one kind of free, surplus, uncombined electric charges, electrons and ions in 130

synchronism with the frequency of the A. C. creating the said field.

17. In the present process of absorbing and combining nitrous oxid and nitric oxid and the like with water and alkali solution and the like, the additional step of conducting the same in opposing A. C. fields under insulated conditions, and simultaneously while the gases are being forced through electro-positive comminuted dielectric adsorption material, and meeting thereon the percolating liquid absorbers.

18. In the present process of absorbing and combining nitrous oxid and nitric oxid and the like, with water and alkali solution and the like, the additional step of conducting the same in an A. C. field under insulated conditions, and simultaneously while the gases and liquids are being passed through comminuted dielectric adsorption material; and with the leading to earth with increased voltage from said liquids and gases and comminuted material, of only the one kind of free, surplus, uncombined electrical charge, electrons and ions in synchronism with the frequency of the A. C. creating the said field.

19. A process of compounding gases of two gaseous components which consists in first electrically charging the two components separately with opposite signs, and then forcing same together through a mass of inert comminuted dielectric adsorbs, all under insulated conditions.

20. A process of compounding gases of several gas constituents which consists in first electrically charging the constituents with opposite signs, and then of mixing the same together all under insulated conditions.

21. In the electrical fixation of nitrogen from air in the synthetic ammonia process, the process of combining nitrogen and hydrogen gases through first charging same with opposite electric signs and forcing same together through masses of comminuted chemically inert dielectric adsorbs under insulated conditions.

22. In the electrical fixation of nitrogen from air in the synthetic ammonia process, the process of combining nitrogen and hydrogen gases through first charging same with opposite electric signs and forcing same together through masses of comminuted chemically inert dielectric adsorbs in an A. C. field under insulated conditions.

23. A process of fixing and attaining combinations of gases which consists in bringing same together on the surface of insoluble dielectric adsorbs in an A. C. field under insulated conditions.

24. A process of fixing and attaining combinations of gases which consists in bringing same together on the surface of in-

soluble dielectric adsorbs in an A. C. field under insulated conditions and leading to earth therefrom only the freed surplus uncombined ions, electrons and charges.

25. In the process of combining gases, the additional steps of bringing the elementary gases together on the surfaces of a mass of comminuted inert insoluble dielectric adsorbs in opposing A. C. fields, under insulated conditions.

26. In connection with a system of the nature described, the method of insulating from earth and the like, any vessel, and its contents as regards only the one kind of electricity charge, electron and ion, which consists in insulating the vessel and contents as a whole on insulator supports, and in discharging to earth from the contents only the other and opposite complementary kind of charge electron and ion, substantially as described.

27. In an apparatus of the nature described, a vessel for treating suitable mixtures of gases and air, in combination with a comminuted dielectric adsorbs within the vessel, means for attemperating and rapidly forcing air and gases therethrough, means for producing in such mixture therein, alternating current fields and stresses, of regulated frequency, voltage and amperage, under insulated conditions.

28. In an apparatus of the nature described for compounding gases, twin tubes with comminuted adsorbs, the one electro-positive, the other electro-negative, in connection with a third tube with means of forcing gases separately through the twin tubes into the third tube, each holding a mass of inert comminuted adsorbs, all under insulated conditions.

29. In an apparatus of the nature described, a vessel for treating suitable mixtures of gases and air in combination with a comminuted dielectric adsorbs within the vessel, means for attemperating and rapidly forcing air and gases therethrough, means for producing in such mixture therein, alternating current fields and stresses, of regulated frequency, voltage and amperage under insulated conditions and means for earth connecting from the mixture through an insulated electric ground forcer and interrupter making and breaking earth connection for one sign only of the alternations of each cycle of one of the alternating currents creating said field.

30. An apparatus of the nature described, comprising an insulated vessel holding a comminuted dielectric adsorbs, in combination with insulated regulated means for forcibly supplying to and rapidly withdrawing therefrom a suitable mixture of gases, air and the like; means for attemperating same; insulated means for providing and maintaining in said mixture and

- vessel alternating current fields, under insulated conditions; insulated means for electrically connecting the said mixture in said vessel to earth, through an electric ground 5 forcer and interrupter making and breaking earth connection in synchronism with the frequency of one of the alternating current circuits, operating the interrupter and creating one of said fields, and balanced 10 in the other lead of same alternating current circuit by a suitable impedance coil; means for placing an insulated inductive resistance in series in each of said alternating current circuits.
- 15 31. In an electric arc furnace for nitrogen fixation from air, an earthing electrode in the path of the gases near the arc and electrically connected to earth through an insulated ground line to an insulated 20 interrupter selector adjusted to pass only the one kind of charge, electron, ion and the like, to earth.
32. An electric arc furnace comprising an A. C. arc in a suitable furnace chamber, 25 under insulated conditions, in combination with means of forcing air and gases into and through the arc, means of leading to earth from the gases in the vicinity of the arc within the furnace of only the positive 30 alternation, charge, electron and ion in the gases resulting from the arc current.
33. An electric arc furnace comprising an A. C. arc in a suitable furnace chamber under insulated conditions in combination 35 with means of forcing air and gases through the furnace and with an earth electrode in the path of and in contact with the gases near the arc having a synchronous interrupter in the earthing line therefrom to pass to earth only the one kind of alternation 40 charge, electron and ion, with means of increasing the voltage thereof to earth.
34. An electric arc furnace comprising an A. C. arc in a suitable furnace chamber 45 under insulated conditions in combination with means of forcing air and gases into and through and from the high voltage arc into and through an A. C. field of low voltage, between cooling electrodes within the 50 furnace, and thence beyond into other and cooling and oxidizing chambers, under insulated conditions.
35. In the apparatus for the purpose described, an electric ground forcer comprising 55 an insulated adjustable interrupter selector in an electric ground line from an A. C. field in suitable vessels under insulated conditions, in combination with an insulated static machine and the like, one terminal 60 whereof being electrically connected with an earthing electrode in said A. C. field, and the other terminal being electrically connected through an insulated interrupter selector to earth, the said selector being adjustable 65 and adjusted to pass therethrough to earth

from the earth electrode automatically only the one kind of charge, electron and ion in synchronism with the frequency of the A. C. creating the said A. C. field.

36. In an apparatus for the purpose described an electric earthing apparatus comprising the combination of insulated vessels and contents with a ground wire therefrom with an interrupter in the ground wire passing therethrough only the 75 one kind of current charge, electron and ion, with means of selecting and discharging only such one kind of alternation of A. C. and of insulating the other complementary charge and the like, with means of 80 increasing the voltage of the former to earth.

37. In an apparatus for the purpose described a synchronous selector grounding apparatus from an insulated A. C. field comprising an earth electrode in the A.C. field with a ground line therefrom having in the ground line an insulated synchronous selector interrupter to pass therethrough in synchronism with said A. C. only the one kind 90 of alternation, charge, electron and ion, to and with a booster coil to increase the voltage of latter to earth.

38. In an apparatus for the purpose described a synchronous selector grounding apparatus from an insulated A. C. field comprising an earth electrode in the A. C. field with a ground wire therefrom having in the ground line an insulated synchronous selector interrupter to pass therethrough in 100 synchronism with said A. C. only the one kind of alternation, charge, electron, and ion, to and with an insulated condenser in series and an insulated step-up transformer increasing the voltage to earth.

39. In a plant for the manufacture of nitrates by the electrical oxidation of air, an electric arc furnace in combination with a succession of continuously connected and simultaneously operated electric tubes and chambers with A. C. fields with comminuted dielectric adsorbent, with means of rapidly forcing through the whole, and means of attemperating, the air and gases from the arc until finally condensed and absorbed; 110 all under insulated conditions.

40. An electrically compounded product comprising a nitrogen compound homogeneous and of increased density and stability.

41. An electrically compounded product comprising an electro-negative nitrogen compound homogeneous and of increased density and stability.

42. An electrically compounded explosive comprising nitrogen electro-negative compounds of increased density and stability and homogeneous.

43. An electrically compounded product comprising a basic nitrate compound of increased density and stability.

44. An electrically compounded product comprising a calcium nitrate compound of increased density and stability.

45. An electrically compounded product comprising electro-negative nitrogen groups of increased density and stability and homogeneous.

In testimony whereof I hereto affix my hand in the presence of two witnesses.

JACOB E. BLOOM.
